UNITARY APPARATUS FOR PROJECTING LIGHT RAYS

Filed August 13, 1921 3 Sheets-Sheet 3

UNITED STATES PATENT OFFICE.

OSCAR H. PIEPER AND ALPHONSE F. PIEPER, OF ROCHESTER, NEW YORK.

UNITARY APPARATUS FOR PROJECTING LIGHT RAYS.

Application filed August 13, 1921. Serial No. 491,903.

To all whom it may concern:

Be it known that we, OSCAR H. PIEPER and ALPHONSE F. PIEPER, of Rochester, in the county of Monroe and State of New York, have invented certain new and useful improvements in Unitary Apparatus for Projecting Light Rays; and we do hereby declare the following to be a full, clear, and exact description of the same, reference being had to the accompanying drawings, forming a part of this specification, and to the reference numerals marked thereon.

This invention has to do with apparatus for projecting light rays and relates more particularly to unitary apparatus for adjustably supporting and operating a source of light, such as an X-ray tube, to illuminate objects for examination.

The present invention is in the nature of an improvement upon the invention set forth in our co-pending application for Patent Serial No. 410,468, filed Sept. 15, 1920, for unitary light projecting apparatus, having for one of its objects to provide a more convenient and substantial construction for adjustably mounting the light source on its supporting standard, including also various advantageous features affording greater protection from injury for the light source. Another object is to provide a safer and more convenient construction for supporting the light source and its electrical connections, increasing the degree of insulation of the electrical conductors as well as the accessibility of related parts. To these and other ends the invention consists in certain improvements and combinations of parts, all as will be hereinafter more fully described, the novel features being pointed out in the claims at the end of the specification.

In the drawings:

Figure 1 is a side elevation of an apparatus embodying the present invention.

Figure 2 is an enlarged sectional detail view on the line 2^a—2^a of Figure 1.

Figure 3 is an enlarged side elevation of a portion of the apparatus shown in Figure 1, with the parts in a different position.

Figure 4 is an elevation of a portion of

the apparatus shown in Figure 3 as viewed from the right.

Figure 5 is a top plan view of a portion of the apparatus shown in Figure 3.

Figure 6 is an enlarged sectional view on the line 6^a—6^a of Figure 4.

Figure 7 is a sectional view on the line 7^a—7^a of Figure 6.

Figure 8 is an enlarged elevation in longitudinal central sections of the light source and supporting parts.

Figure 9 is a section on the line 9^a—9^a of Figure 8.

Figure 10 is an elevational view of the parts supporting the light source as seen from the line 10^a—10^a of Figure 8 and reduced in scale.

Figure 11 is an enlarged sectional elevation of one of the pivotal joints in the supporting standard.

Figure 12 is a reduced sectional view on the line 12^a—12^a of Figure 11.

Figures 13 and 14 are perspective views of detached parts shown in Figures 11 and 12.

Similar reference numerals throughout the several views indicate the same parts.

The present embodiment of the invention comprises preferably a portable container or cabinet 20, Figure 1, on which is carried a standard, indicated generally at 21, supporting a source of light which, in the present instance, is an X-ray tube of the so-called Coolidge type. The means for controlling the electrical energy for the light source is contained in cabinet 20, including, for example, the transformer indicated at 22 and rheostats, meters, and the like, (not shown).

The main column of the standard is preferably telescopically supported for vertical adjustment into and out of the container by any suitable means such, for example, as shown and described in our co-pending application. The standard comprises a plurality of movably connected parts for adjustably supporting the light source, shaped and arranged so that the container or cabinet

may be conveniently located at one side of the object to be illuminated with the standard overhanging the latter and adjustably

supporting the light source from above adjacent the object. For example, the cabinet may be placed behind or at one side of a dental chair, accessible to, but out of the way of the operator, and the light source is flexibly supported for quick adjustment to any desired position about the head of a patient in the chair. The light source or X-ray tube is energized and controlled by devices enclosed in the container, and the energy supplied to a light source of this character being of the high tension variety, suitable provision is made for connection between the light source and the controlling devices in the container by effectively insulated means.

To these ends there is pivotally supported on the standard column in any suitable manner at 23 a laterally directed horizontally adjustable hollow arm 24 receiving a telescopically extensible portion 25 on which is pivotally supported at 26, by means herein-after described, a downwardly extending arm 27. The latter is horizontally adjustable on its pivot and has pivotally connected therewith at 28 adjacent its lower end by means hereafter described, an auxiliary arm 29. On the latter is supported for pivotal movement, about an axis substantially perpendicular to the pivotal axis at 28, a forked arm 30 having branches 31 extending downwardly in spaced relation. The lower ends of the branching arms 31 carry trunnions 32 on which is pivotally supported at its ends, above the centers of the latter, a loop shaped frame 33 provided on the inner opposed sides of its top and bottom with V-shaped tracks or guideways 34. A crosshead 35 has its top and bottom formed for engagement with the guideways 34 and slides on the latter endwise of frame 33. The crosshead is preferably constructed of any suitable insulating material, such for example, as phenol condensation product, rubber, or the like, and preferably has formed integrally therewith means for supporting engagement with the X-ray tube. The latter is in the present instance, of the type having an outer tubular protective shield 39 with a substantially spherical enlarged portion 38 intermediate its ends. In conjunction with a light source of this character crosshead 35 preferably has formed integrally therewith a collar 36 encircling the tube in engagement with the enlarged portion of the latter. An opposing collar 41 encircles the tube on the other side of its spherical enlargement, the collars being adjustably bolted together as herein-after described and clamping the tube between them. To afford firmer engagement with the tube and prevent injury of the latter the collars are faced interiorly with a cushioning insert or washer 37 of any suitable material such as cork. The inner tube is indicated at 40. It is to be noted that the described means of supporting the tube

leaves a long uninterrupted surface between the support and the radiator end 59 of the tube to which the high voltage conductor is connected, thereby tending to prevent surface leakage. At the same time the two collars afford well separated and ample gripping surfaces for securely holding the tube without injury.

Collar 41 has a cylindrical extension 41^a in the end of which is telescopically received the cylindrical end of a nozzle or adapter 42, in the present instance of the cone shaped variety commonly employed. For detachably securing the adapter on collar 41 the adapter end is formed with an annular recess 43 with which engages the end 44 of a spring clip 45 bent to project through an opening 46 in the collar extension. The adapter is thus supported entirely on the collar free of the tube and can be readily detached for the substitution of different types.

The means for attaching the collars together in clamping engagement with the tube comprises preferably a plurality of rods or bolts 47 threadedly engaging in openings 48 in lugs or bosses provided on the collars. By this means the latter may be adjusted into firm clamping engagement with the tube for securely supporting the latter.

As shown in Figure 5 frame 33 is formed from end to end in the shape of a circular arc drawn about a center arranged to coincide substantially with the object to be illuminated and the light source may be adjusted by moving the crosshead 35 to different positions lengthwise of the frame for illuminating the object from different angles and for the production of photographs with stereoscopic effects. For securing the tube in different positions of adjustment in the frame the upper side of collar 36 is faced with a plate 48 in which and in the collar are formed spaced recesses 49. Engaging with these recesses is a longitudinally movable plunger 50 supported adjacent the center of the upper side of frame 33. To adjust the position of the tube in the frame plunger 50 is raised out of engagement with a recess of collar 36 and the tube swung to another position in which the plunger is re-engaged with one of the recesses in the collar and holds the latter and the tube in adjusted position.

An advantageous feature of the present invention comprises means for protecting the cathode filament of the tube and its electrical connections. The tube of the type described has a laterally extending branch 51, Figure 8, providing an opening 51^a in which is located and supported the cathode indicated generally at 52 and through which the conductor 53 extends from the filament over supports 54 on the standard to the source of electrical energy in the cabinet. The filament parts and connections are of

course delicate in character and easily injured or destroyed by the impact of an inadvertent blow or collision. For the purpose of adequately protecting these parts 5 there is provided a cap or hood 55 for the opening 51^a, of any suitable material and in the present instance aluminum, having its rim resting on the periphery of the end of tube branch 51. To secure the protective 10 cap in place there is provided on each side of the tube branch a metal strap 56 having one end looped about the adjacent bolt 47 connecting the tube collars and having its other end slotted and embracing a screw 57 15 carried by the cap. By this means the cap may be securely fastened in place by attachment to the tube supporting means and the tube branch is effectively protected against an inadvertent blow which might otherwise 20 injure or destroy it. The cap has adjacent its rim an outlet opening 58 through which the conductor 53 is passed as shown in Figure 3.

As apparent from the drawings the embracing arrangement of the collars and their connecting bolts about the enlarged portion of the tube, the disposition of these parts within frame 33, and the supporting of the tube adapter 42 and cathode cap 55 on the 25 collars affords a considerable degree of protection for the tube against inadvertent blows and collisions with other objects.

The end of the tube opposite the object to be illuminated carries a radiator 59 and to 30 this end of the tube is connected the high tension conductor 60, as well understood in the art. The conductor is supported on insulating struts 61 carried by the standard and passes into the upper end of a hollow 35 insulating post 62 supported on the top of the cabinet. The lower end of the post preferably extends some distance through the top of the cabinet so that the bore of the post communicates with the cabinet interior. 40 Adjacent its upper end the post bore is preferably enlarged, as indicated at 63, Figure 2, to form a housing for reeling means for maintaining the high tension conductor 60 taut in all positions of adjustment of the 45 light source and its standard. Within the post housing 63 is an angular bracket 64, preferably of conductive metal, the lower end of which is fixed to the post in any suitable manner 65. Rotatably supported on 50 the bracket as at 66 is a drum or reel 67 preferably also of conductive metal to which is fixed and on which is wound the high tension conductor 60. A spring of any known or suitable variety (not shown) on the reel 55 tends to wind up the conductor to maintain the latter taut in the manipulation of the light source. The housing 63 is constructed with a detachable upper half portion 69 forming the upper end of the post and provided with an opening through which con-

ductor 60 extends. Through this opening is inserted a reduced and threaded portion 70 of a member 71 which engages an opening in an angular end of bracket 64 thereby detachably securing portion 69 of the housing in place. Member 71 has a central aperture curved to present a smooth bearing surface for conductor 60. A conductor 72 connected with the controlling devices within the cabinet, is extended upwardly through 75 the post 62 and connected in any suitable manner with the lower end of bracket 64 supporting the reel, the current passing through the bracket and reel to the end of conductor 60 connected with the latter. 80 This provides an advantageous construction for protectively housing the reeling means for the high tension connection entirely within the tube and at the same time affords convenient access to the latter whenever required. 85

The location of the pivotal connection between standard arms 31 and frame 33 above the center of the latter tends to throw the tube away from the standard when it is 90 turned on its pivotal connection to direct the light rays in a downward direction and thus tends to maintain the maximum air gap between the high tension end and the standard. Shoulders 31^a on one arm 31 and a 95 stop 33^a on the frame, Figure 3, limit the safe range of movement of the frame.

As explained in our said co-pending application, the pivots 26 about which arm 27 and the light source may be swung is adapted 100 to be positioned substantially above the center of an object to be illuminated for convenience in adjusting the light source radially to different positions about the same and an advantageous construction is 105 provided for this pivotal connection, as shown in Figures 11 to 14 inclusive. The extensible portion 25 of the horizontal arm of the standard terminates in spaced cheek bearing plates 73, Figure 11, in which the 110 pivot spindle 26 is supported. The end of arm 27 is pivotally mounted on the spindle between plate 73 and the upper side of the arm is recessed to form a flange 74 concentric with the spindle. Slidably supported on the inner surface of flange 73 is 115 a ring 75 of resilient metal the ends of which are spaced and beveled as indicated at 76, Figure 13. Fitted into the space between the ends of the ring is a wedge shaped member 77 having a recess 78 adapted to receive the lower end of a manually adjustable screw 79 carried by the upper plate 73. This construction provides a simple and 120 convenient means for frictionally restraining movement of the radial arm 27 so that it is retained in any position of adjustment but may at the same time be easily adjusted or swung as desired by a comparatively 125 light pressure. By turning screw 79 in one 130

direction it may be entered to advance wedge 77 between the ends of ring 75 and thereby expand the latter to produce greater frictional contact with flange 74 of arm 27.

5 The latter may thus be securely locked against movement if desired.

The pivotal connection between arms 27 and 29 referred to above comprises spaced cheek bearing plates 80 on the lower end 10 of arm 27 between which a corresponding plate on arm 29 is pivotally supported by spindle 28. The bearing plate of arm 29 has in its edge a plurality of spaced recesses or sockets 82 arranged to be engaged 15 by the lower end of a plunger 83 carried by arm 27 and spring pressed toward the recesses. Plunger 83 may be lifted out of engagement with one recess and arm 29 swung about its pivot to another position 20 in which plunger 83 is permitted to engage with the adjacent recess for holding the arm in adjusted position. Arm 29 is provided with a stud 84 extending generally downward in a direction at right angles to 25 the axis of the pivot 28 and the upper end of arm 30 is rotatably supported on stud 84. A spring pressed plunger 85 on arm 30 has its end 86 disposed for selective engagement 30 with a plurality of spaced recesses (not shown) in arm 29 so that when plunger 85 is moved downwardly out of engagement with arm 29 arm 30 may be pivotally adjusted to the desired position on stud 84 after which plunger 85 is released for engagement 35 with the adjacent recess in arm 29 for holding the arm 30 and the light source in the desired position. Means are preferably provided for limiting this pivotal movement of arm 30 comprising a stop screw 87 projecting from arm 29 into an arcuate recess or slot 88 in the arm 30. Arm 30 of course carries the downwardly branching spaced arms 31 between which the frame 33 is pivotally supported as previously described. It is apparent from the 45 above description that the standard is so constructed of movably connected parts that the supporting means for the light source is universally adjustable to practically any 50 operating position adjacent the object to be illuminated.

The invention thus provides, in conjunction with an advantageous standard construction, practical and effective means for supporting the X-ray tube on the standard by which the tube is firmly gripped and supported by ample bearing surfaces. The tube supporting means is not only itself so disposed as to afford considerable protection 55 for the tube but furthermore carries the tube nozzle or adapter so that the latter is clear of the tube and protects the latter, and also supports a protective cap for the tube cathode. After the standard parts are 60 adjusted the construction provides for con-

venient movement of the tube to different radial positions about the object for illuminating the latter from different angles. The tube supports are for the purpose of insulation well spaced from the end of the 70 tube to which the high tension connection is made and are so connected with the standard arms as to maintain the high tension connection spaced from the standard during 75 adjustments. The high tension conductor is maintained taut between its points of support by reeling means protectively housed and accessibly arranged on post 62.

We claim as our invention:

1. In a unitary light projecting apparatus, the combination of a container, a standard for supporting a source of electric light for adjustment to different positions about an object to be illuminated, devices in the container for controlling the power supplied to the light source, a relatively high hollow post on the container having its bore communicating with the container interior, a spring actuated reel housed within the bore of said post, 80 an extensible conductor wound on the reel and extended through the outer end of the post into connection with the light source, and a conductor extending through the inner end of the post bore and connecting the 85 controlling devices in the container with the conductor wound on said reel.

2. In a unitary X-ray apparatus, the combination of a cabinet, an X-ray tube, means supporting said tube for adjustment to different operating positions, electrical control devices for said tube in the cabinet, a relatively high hollow post on the cabinet having its bore in communication with the interior of the latter and enlarged at its 100 outer end to form a housing, a spring actuated reel in said housing, a conductor wound on the reel and extended through the outer end of the post bore into connection with the tube, and a conductor extended through the inner end of the post bore and connecting the control devices in the cabinet 105 with the conductor on said reel.

3. In a unitary light projecting apparatus, the combination of a container, a standard for supporting a source of electric light for adjustment to different positions about an object to be illuminated, an upwardly projecting strut on said standard for supporting a high tension conductor, devices in the container for controlling the power supplied to the light source, a relatively high hollow post on the container having its bore communicating with the container interior, a spring actuated reel housed within the bore of said post, 115 an extensible conductor wound on the reel and extended through the outer end of the post over said strut into connection with the light source, and a conductor extending through the inner end of 120 the post.

the post bore and connecting the controlling devices in the container with the conductor wound on said reel.

4. In a unitary light projecting apparatus, the combination of a container, an adjustable standard carried thereby for supporting a source of electric light for adjustment to different positions about an object to be illuminated, devices in the container for controlling the power supplied to the light source, a hollow post on the container of insulating material having its bore communicating at its inner end with the container interior and enlarged adjacent its outer end to form a housing, said housing comprising a detachable section affording access to the interior thereof, a spring actuated reel supported in said housing, an extensible conductor connected with and wound on the reel and extended through an opening in said detachable section into connection with the light source, and a conductor extending through the inner end of the post bore and connecting the controlling devices in the container with said reel.

5. In a unitary light projecting apparatus, the combination of a container, an adjustable standard carried thereby for supporting a source of electric light for adjustment to different position about an object to be illuminated, devices in the container for controlling the power supplied to the light source, a hollow post on the container of insulating material having its bore communicating at its inner end with the container interior and enlarged at its outer end to form a housing, said housing comprising a detachable section affording access to the interior thereof and forming the upper end of the post, a bracket of conducting material fixed to the post in the housing, an apertured member having a reduced portion inserted through an opening in said detachable section and secured to the bracket to hold the section in place, a spring actuated reel of conducting material rotatably mounted on the bracket, a conductor connected with and wound on the reel and extending through the aperture in said member into connection with said light source, and means electrically connecting said controlling devices and bracket.

6. A unitary light projecting apparatus comprising a standard, a frame carried by the standard and provided with spaced guideways, a body containing a light source, opposed parts adjustably connected with each other in clamping engagement with said body, and a crosshead supporting said parts and adjustably slidable on the guideways of said frame for adjusting said body to different operating positions.

7. A unitary light projecting apparatus comprising a standard, a frame adjustably carried by the standard and provided with

spaced guideways, a substantially tubular body containing a light source and formed with an enlarged portion intermediate its ends, collars encircling said body and connected with each other in clamping engagement with opposite sides of said enlarged body portion, and a crosshead supporting said collars and adjustably slidable on the guideways of said frame for adjusting said body to different operating positions.

8. A unitary light projecting apparatus comprising a standard, a frame adjustably carried by the standard, a body containing a source of light, opposed parts adjustably connected with each other in clamping engagement with said body, means adjustably supporting said parts and body for pivotal movement to different positions on the frame, and a locking pin longitudinally slidable on the frame for engagement with recesses in said supporting means for securing said body in different positions of adjustment.

9. A unitary light projecting apparatus comprising a standard, a frame adjustably carried by the standard, a body containing a source of light, opposed parts adjustably connected with each other in clamping engagement with said body, means adjustably supporting said parts and body for pivotal movement to different positions on the frame, securing means for holding said body in adjusted position, and an adapter for said body detachably carried by one of said clamping parts.

10. A unitary light projecting apparatus comprising a support, an X-ray tube housing having an opening provided with connections for the tube filament, tube holding means engaging said housing and adjustably carried on the support, and a protective cap for said housing opening having a connection with said holding means for detachably securing the cap in place.

11. A unitary light projecting apparatus comprising a standard, an X-ray tube housing having an enlarged portion and an opening provided with connections for the tube filament, collars adjustably carried by the standard and engaging the opposite sides of said enlarged housing portion, bolts connecting said collars for clamping the latter on the housing, a protective cap for said housing opening, and clips adjustably and detachably securing said cap to said bolts intermediate said collars.

12. In a unitary light projecting apparatus, a standard having downwardly extending branching arms, an X-ray tube, spaced collars in clamping engagement with said tube, a crosshead supporting said collars, a loop-shaped frame embracing said tube and slidably supporting said crosshead, and a pivotal connection between the arms of the standard and opposite sides of said

frame disposed eccentrically of the latter for spacing the tube from the standard during pivotal movement of said frame.

13. In a unitary light projecting apparatus, a standard having an adjustable arm portion, a light source, a frame, means supporting the light source for movement to different positions on the frame, a pivotal connection between said standard arm por-

tion and frame arranged eccentrically of the latter for spacing the tube from the standard during pivotal movement of the frame, and cooperating stop means on said arm portion and frame limiting pivotal movement of the latter.
